UNITED STATES PATENT OFFICE.

HOWARD P. STROUGH, OF FRESNO, CALIFORNIA.

TUNING-PEG FOR MUSICAL INSTRUMENTS.

1,345,972.

Specification of Letters Patent.

Patented July 6, 1920.

Application filed June 4, 1919. Serial No. 301,600.

To all whom it may concern:

Be it known that I, HOWARD P. STROUGH, citizen of the United States of America, residing at Fresno, in the county of Fresno, 5 and State of California, have invented new and useful Improvements in Tuning-Pegs for Musical Instruments, of which the following is a specification.

The object of the invention is to provide 10 a tuning or string peg for musical instruments of the violin, guitar, banjo, mandolin and similar types whereby when the desired tension has been applied to the attached string, as in tuning the instrument, 15 the peg may be locked or secured to prevent backward turning movement or loosening to relieve the acquired tension upon the string and thus alter the pitch thereof, and incidentally to provide means for the purpose indicated which will serve to prevent 20 the unseating or accidental detachment or dismounting of the peg with the disadvantages resulting therefrom.

With these ends in view the invention 25 consists in the construction, combination and relation of parts of which a plurality of forms are shown in the accompanying drawings, it being understood that changes in proportions and details may be resorted 30 to within the scope of the claims without departing from the principles involved.

In the drawings:

Figure 1 is a sectional view of a peg seated in the ordinary way in a peg box 35 which may be represented by the neck of a musical instrument of one of the types employing tuning pegs which are ordinarily held at the desired adjustment, with the attached string at the preferred tension by 40 means of frictional contact of the surfaces of the peg shank with the openings in the walls of the box.

Fig. 2 is a cross-sectional view on the plane indicated by the line 2—2 of Fig. 1.

Fig. 3 is a similar sectional view on the plane indicated by the line 3—3 of Fig. 1.

Fig. 4 is a longitudinal sectional view of a peg having a modified form of locking or anchoring means.

Fig. 5 is a cross-sectional view on the plane indicated by the line 5—5 of Fig. 4.

In both of the illustrated embodiments of the invention the peg 10 is provided with the usual tapered shank 11 fitting in the 55 walls 12 and 13 of the peg box represented by the space therebetween, and in the form

particularly shown in Figs. 1 to 3 inclusive, the inner end or tip of the peg shank is split or constructed so as to be transversely expansible as shown at 14, with the elements thereof as indicated in Fig. 3 exposed to the action of a spreader or cone 15 provided with a stem 16 which extends through a longitudinal bore 17 in the peg and is fitted at a point within convenient reach of 60 the fingers of the operator with a peripheral milled nut 18 seated, for example, in a transverse recess 19 in the head of the peg so as to be exposed at diametrically opposite points to contact with the fingers 65 grasping the said peg head. Obviously by turning the nut the stem may be adjusted longitudinally in the peg to cause the inward or outward movement of the spreader to either expand or permit the contraction 70 of the split end of the peg shank, and the spreading action thereof is designed to cause a positive frictional engagement of the exterior surfaces of the elements 14 with the walls of the opening 20 in the wall 13. 75 Preferably this opening 20 is tapered inwardly, or is flared toward the exterior surface of the wall so as to permit freedom of movement of the elements 14 in the spring of the shank. Moreover the flaring of this 80 seat in the peg box wall serves to insure a more positive engagement of the split end of the peg and guard against accidental turning movement after an adjustment has been secured, and further serves to cause 85 such a relation, between the peg and the wall, when the extremity of the former is spread, as to prevent the accidental displacement or dismounting of the peg. Obviously any desired degree of frictional 90 contact may be produced to insure the maintenance of the peg in an adjusted position, and the locking thereof may be effected by the operator without releasing his grip upon the head of the peg after having effected the desired adjustment thereof. 100

In the modified construction illustrated in Figs. 4 and 5 there is provided a locking element consisting of a disk 21 connected with a stem 22 extending through an axial bore of the shank of the peg and fitted with an adjusting nut 23 similar to that described in connection with the form shown in Fig. 1, said stem having a lateral fin 24 engaged with a groove 25 in the bore of the 105 peg to prevent the turning of the stem with the nut in the adjustment of the latter. 110

The locking disk 21 bears against the exterior surface of the wall 26 of the peg box and serves to draw the peg axially into the peg box so as to cause a frictional binding 5 action of a positive character between the tapered exterior surface of the peg shank and the opening 27 in the front wall 28 of the box.

Also in the form illustrated in Fig. 1 a 10 fin 29 may be provided by flattening the stem to engage a guide groove 30 in the bore 17 so as to hold the stem 16 against turning movement as the cone is adjusted axially with reference to the split tip of 15 the peg shank.

From the foregoing description it will be seen that in both of the illustrated forms of the invention the locking of the peg in its adjusted position is effected by the frictional contact of coöperating elements, one 20 of which is movable to produce an effective contact by means of an adjusting member located in and carried by the head of the peg so as to be within reach of the fingers 25 of the operator in adjusting the peg to tune the attached string. In the form illustrated in Fig. 1 the frictional engagement is effected by the axial adjustment of the spreader or cone coöperating with the split 30 tip of the peg shank to cause engagement of the surface of the latter with the opening in the peg box wall, while in the form illus-

trated in Fig. 4 said contact is effected by the axial adjustment of the disk 21 to produce frictional contact with the surface of 35 the rear wall of the peg box and at the same time this effect is supplemented by inducing a bodily movement of the peg to cause its tapered surface to more firmly seat in the opening in the front wall of the peg 40 box.

Claimed:

The combination with a musical instrument having a peg box of which the rear wall is provided with an outwardly flared 45 peg seat, of a peg having its shank provided at its end with a plurality of longitudinal slits and fitted in said flared seat, a conical spreader engaged in the slit terminal and provided with a stem extending 50 through the shank of the peg, said stem being formed with oppositely disposed fins, the shank having guide grooves in which the fins engage, the head of the peg having a recess, and a knurled nut set in the 55 recess of the head and threadingly engaging the extremity of the shank, whereby longitudinal movement without angular movement is imparted to the shank to draw the spreader into the slit terminal of the 60 shank for firm frictional contact of the latter with the flared seat of the peg box.

In testimony whereof I affix my signature.
HOWARD P. STROUGH.
